R. B. SHOOK.

PIPE WRENCH.

APPLICATION FILED DEC. 18, 1919.

1,342,356.

Patented June 1, 1920.

UNITED STATES PATENT OFFICE.

ROY B. SHOOK, OF DAYTON, OHIO.

PIPE-WRENCH.

1,342,356.

Specification of Letters Patent.

Patented June 1, 1920.

Application filed December 18, 1919. Serial No. 345,754.

To all whom it may concern:

Be it known that I, Roy B. Shook, a citizen of the United States, residing at Dayton, in the county of Montgomery and State of Ohio, have invented certain new and useful Improvements in Pipe-Wrenches, of which the following is a specification.

This invention relates to new and useful improvements in pipe wrenches.

10 The object of the invention is to provide a wrench of uncommon strength and having the structural features hereinafter described and claimed.

15 Preceding a more particular description of the invention, reference is made in general terms to the accompanying drawings.

In said drawings Figure 1, is a side elevation of my improved wrench; Fig. 2 is a bottom plan view of the wrench; Fig. 3 is a 20 section on the line 3—3 of Fig. 1; Fig. 4 is a section on the line 4—4, of Fig. 1; Fig. 5 is a section on the line 5—5 of Fig. 1; Fig. 6 is a section on the line 6—6 of Fig. 1; Fig. 7 is a section on the line 7—7 of Fig. 1; Fig. 25 8 is a fragmental section of the adjustable nut and Fig. 9 is a section of a portion of the adjusting nut.

In a more particular description of the invention similar reference characters indicate corresponding parts in the several views.

The handle —1— of the wrench is detachable from the member —2— to which the fixed jaw —7— of the wrench is secured. 35 It is desirable to have the handle —1— so made detachable in order that different handles may be substituted to suit different users. The handle shown in the drawing is made of wood, a common material in the 40 construction of tool handles. The said handle —1— has a metal extension —4— which terminates in an interlocking portion —5— which enters sidewise a groove —6— in the metal interlocking portion —2— of the 45 fixed jaw member 7. When the detachable handle —1— is connected with the fixed jaw member —7—, as shown in Fig. 1, the sides are inclosed by plates 8—8, which are secured by pins —9— which enter openings —10— in the handle extension and the interlocking portion 2 of the fixed jaw member —7— respectively. The fixed jaw member —7— is recessed on each side as indicated by —11— as shown in Fig. 2, and

at each end of said recesses, heads 12 and 13 55 are formed. The head —12— has inner tapered shoulders —14— formed thereon, and the head —13— has tapered shoulders —15— formed thereon. The fixed jaw member —7— terminates in the end head 60 —13— to which a toothed plate —3— is secured by means of a screw —16—, and a pin —17— which projects from the said plate —3— and enters a cavity in the head —13— of said fixed jaw member. The 65 teeth on the plate —3— coöperate with the teeth on the movable jaw member —22—. The said movable jaw member extends in a horizontal toothed shank —21— which is moved to its adjusted positions by an ad- 70 justing nut —25— which receives the toothed shank. The shank —21— is received by the upper opening —20— in a frame —18—, said frame also having a lower opening —20'— which receives the 75 recessed portion of the fixed jaw member —7—. The threaded portion 21 of the movable jaw member has longitudinal serrations —23— extending through the adjusting threads —24— as shown in Fig. 8 more 80 clearly, and the adjusting nut —25— as shown in Fig. 9 has threads —26— that coöperate with the threads —24— and serrations —26— that coöperate with the serrations —23—. The purpose of providing the 85 shank —21— and the adjusting nut —25— with the serrations —26— is to prevent the nut from turning too freely on the shank —21— when the wrench is being used. The sides of the frame —18— lie over the 90 sides of the recessed portion —11— of the fixed jaw member, and said frame —18— is pivotally united to said recessed portion by a pivot pin —19— and abuts with the heads —12— and —13— on each side of said pivot 95 —19—. The lower sides of the frame —18— are tapered as at —28— and —28'— to adapt them to enter the recesses in the heads —12— and —13— at the ends of the recessed portion of the fixed jaw member 100 —7—. The said frame —18— has a shoulder —29— on each side which abuts with the shoulders —14— on the head —12— of the fixed jaw member —7—, and the tapered surface —28'— of said frame —18— locks 105 with the adjacent surface in which it fits, in the head —13—. These engaging surfaces or parts cause an interlocking between

the frame —18— supporting the movable jaw, and the fixed jaw member which relieves the pivot —19— of strain when the tool is operated.

5 Beneath the recessed portion —11— of the fixed jaw member, a plate spring —31— is secured, said plate spring being secured at one end to the head —13— by the screw —16—. The said plate spring —31— presses against the lower end of the frame —18— and the bottom side of the recessed portion of the fixed jaw member and holds the movable jaw —22— in contact with the pipe when the wrench is being turned so 10 that the said jaw will not slip while being operated.

As hereinbefore stated, the frame —18— engages with the shoulders —14— on one side of the pivot —19— as shown in Fig. 7. 20 On the other side of the said pivot, the engagement is between the tapered surface —28— of the frame and the corresponding tapered surface of the head —13—. A firm gripping is thus effected between the fixed 25 jaw member —7— and the frame —18—,

when the wrench is operated from the handle —1—.

Having described my invention, I claim:

A pipe wrench comprising a fixed jaw member having a portion recessed on opposite sides and heads formed at the terminals of said recessed portion, said heads having inwardly lying recesses, the recesses of one having shoulders formed therein and the recesses of the other being tapered upwardly and outwardly, a frame pivotally united to the recessed portion of said fixed jaw member, and entering the recesses in the said heads, said frame having shoulders formed on the portions which enter the recesses in one of said heads to abut against the shoulders therein, and said portions of the frame which enter the recesses in the other of said heads being adapted to interlock therewith, an adjustable jaw member supported in said frame, and an adjusting nut engaging said adjustable jaw member within said frame. 30 35 40 45

In testimony whereof I affix my signature.

ROY B. SHOOK.
